PAIL

Catherine T. Auth, Pittsburgh, Pa.

Application December 8, 1950, Serial No. 13,340

Term of patent 3½ years

(Cl. D58—17)

To all whom it may concern:

Be it known that I, Catherine T. Auth, a citizen of the United States, residing at Pittsburgh, in the county of Allegheny and State of Pennsylvania, have invented a new, original, and ornamental Design for a Pail, of which the following is a specimen, reference being had to the accompanying drawings, forming a part thereof.

Fig. 2 is a top plan view;

I claim:

The ornamental design for a pail, as shown.

CATHERINE T. AUTH.
